MOTORCYCLE SADDLE BAG

Theodore S. Harmon, Jr., 100A Dahlgen Ave.,
Portsmouth, Va. 23702

Filed June 8, 1970, Ser. No. 23,365

Term of patent 14 years

Int. Cl. D12—16

U.S. Cl. D90—3

FIG. 1 is a perspective view of a saddle bag embodying my design;

FIG. 2 is a perspective view of the saddle bag shown in FIG. 1 taken from substantially the opposite direction.

I claim:

The ornamental design for a motorcycle saddle bag, as shown.
